CLAIM

The ornamental design for a controller for computer, as shown and described.

DESCRIPTION

FIG. 1 is a front side perspective view of a controller for computer showing our new design;

FIG. 2 is a back side perspective view thereof;

FIG. 3 is a front view thereof;

FIG. 4 is a back view thereof;

FIG. 5 is a top view thereof;

FIG. 6 is a bottom view thereof;

FIG. 7 is a right view thereof; and,

FIG. 8 is a left view thereof.

The broken lines in the drawings show environmental structure that forms no part of the claimed design.

1 Claim, 8 Drawing Sheets

Related U.S. Application Data

division of application No. 29/595,220, filed on Feb. 27, 2017, now Pat. No. Des. 819,642.
